BUILDING BLOCK

Alfred Gibson and Arthur Gibson, Boston, Mass.

Application July 12, 1935, Serial No. 31,008

7 Claims. (Cl. 72—18)

This invention relates to a building block more particularly for facing purposes, for instance, for use as veneer over the interior or exterior walls of a building or as a tread surface over a floor. An object is to provide an artificial or cast facing block which is not only reinforced against crumbling or shattering but which can be securely bonded or locked in place to resist effectively displacing or shifting forces in various directions. Another object is to provide a facing block of the foregoing character which can be fabricated at low cost and which lends itself to immediate and inexpensive application more especially to a bed layer of suitable plastic material serving, upon setting, to bond it to the wall, floor, or other backing on which such layer is initially deposited. The building block of the present invention is a cast structure, for instance, a cement block, of substantial thickness reinforced by a flexible, reticulated metal layer embedded therein substantially parallelly with its faces, the layer projecting through all of the edges of the block, preferably approximately midway of its thickness, and being bent sharply backwardly and extending at least to about the back face, although it is distinctly preferable that it continue inwardly over the back face and thus afford areas for enmeshing bonding material not only immediately next to the edge areas in back of the layer but also immediately next to the back face. Such blocks can be set in a layer of cement, mortar, or other suitable plastic bonding material to form a wall facing or a floor tread which, after being pointed, has each of its blocks firmly locked or keyed both against edgewise and facewise displacement. Such a block is preferably recessed inwardly at all of its edges in back of its front face to define a marginal shoulder and inwardly recessed edges, the metal layer reinforcement projecting through all of the recessed edges immediately in back of the shoulder and continuing to the back face preferably within, or substantially flush with, the outer boundary or edge of the shoulder so as not to interfere with such uniform or variable spacing of adjacent blocks in a finished wall or floor facing as may be desired.

With the foregoing and other features and objects in view, the present invention will now be described in further detail with particular reference to the accompanying drawing, wherein

Figure 1 shows in perspective a block embodying the present invention.

Figure 2 is a section on the line 2—2 of Figure 1.

Figure 3 illustrates in perspective a fragment of a wall faced with such blocks.

Figure 4 is a section on the line 4—4 of Figure 3.

The block shown in Figures 1 and 2 comprises

substantially parallel front and back faces 10 and 11, respectively. If desired, the front face 10 may include, as depicted, a raised panel 10a or be provided with a rubble or any other suitable finish. It is preferably of substantial thickness, say, about $\frac{3}{4}$ to $1\frac{1}{2}$ inches, and is preferably recessed inwardly at all of its edges in back of its front face 10 to define a marginal shoulder 12 and inwardly recessed edges 13. The edges 14 in front of the shoulder may, as shown, be inclined in backwardly divergent relation, whereas the recessed edges 13 in back of the shoulder may be inclined in an opposite or converging relation. The end edges preferably present substantially the same configuration as the side edges. If desired, however, both the edges 14 and 13 may be substantially perpendicular to the faces of the block, with the latter edges being offset inwardly by a distance corresponding to the shoulder 12.

The block is cast from cement, plaster of Paris, or other suitable plastic material with a flexible, reticulated metal reinforcement embedded therein, the reinforcement taking the form, for instance, of wire cloth 15 disposed substantially parallelly and substantially coextensive with its faces and being of such dimensions as to project beyond all of the edges of the block. It is preferable that the layer of wire cloth 15 lie substantially in line with the shoulder 12 so that its projecting marginal portions emerge at the corner 16 formed between such shoulder and the inwardly recessed edges 13. Once the block has set or hardened, the marginal portions are bent sharply backwardly to present areas 15a extending slightly beyond the back face 11 and then turned inwardly to present areas 15b immediately in back of or overlying the back face 11. It will, of course, be appreciated that rather than using wire cloth, such equivalents thereof as metal lath, wire netting, perforated sheet metal, etc., might be used and further that the wire cloth might be of such dimensions that its inturned areas 15b will overlie substantially the entire back face 11. In any event, the dimensions of the wire cloth should be such that its marginal portions when bent sharply backwardly extend at least to approximately the back face, thereby presenting areas for enmeshing bonding material immediately next to the inwardly recessed edges 13.

The block hereinbefore described may be used, as illustrated in Figure 3, as a facing or veneer for the exterior of a wall. The wall may, as shown, comprise a backing of wooden boards 17, although such other materials of construction as brick, concrete, or suitable compositions might be employed as the backing. The backing is preferably covered with a bed layer of plastic material 18, such as hydraulic cement, plaster of Paris, asphalt cement, or the like,

whereupon the facing blocks of the present invention, for instance, blocks of the various sizes depicted in Figure 3 may be set in and bonded by the layer to the backing. In some instances, 5 it may be desirable to drive nails, staples, or other fastening elements through the marginal portions 15a and/or 15b of the wire cloth to suspend the blocks temporarily on the wooden backing while the bonding layer 18 is hardening as well as to provide means for maintaining the blocks in place, should the bed layer and the mortar seams between blocks lose their hold on the blocks. In setting the blocks in the 10 bed layer of material 18, there is a tendency for such material not only to enmesh with the areas 15b of the wire cloth overlying the back of the block but also to exude somewhat into the space or clearance between the inwardly recessed edges 13 of adjacent blocks, as appears in Figure 4. 15 The rest of the space or clearance between adjacent blocks may be filled with mortar 19 when the wall is pointed, the mortar thus being enmeshed by such portions of the areas 15a of the wire cloth as are not filled by the plastic material 18. Of course, pointing of the wall may be effected before or after the plastic material 18 has set.

While it is possible, as already suggested, to omit the areas 15b of the wire cloth overlying the back of the block, yet these wire cloth areas are desired in addition to those areas 15a lying next to the inwardly offset edges 13 in that they not only enhance anchorage of each block against edgewise displacement or movement, but also function to enmesh the plastic material by which the blocks are bonded to the wall backing and thus to safeguard the block against face-wise movement. Indeed, it may be preferable in some instances, as already stated, to provide areas 15b of such dimensions as to overlie substantially the entire back face of the block. 40

In some instances, the wire cloth layer 15 need not extend through the entire body of the block but may consist of a rectangular frame or ribbon bounding a central opening and having an inner zone embedded in the block and an outer zone corresponding to the areas 15a and 15b. Such a frame or ribbon, although intended to be included within the scope of the appended 45 claims, furnishes a discontinuous reinforcement for the body of the block and is hence regarded by us as inferior to the continuous block reinforcement hereinbefore described and shown in the drawing.

55 We claim:

1. A cast building block of substantial thickness reinforced by a flexible, reticulated metal layer embedded therein substantially parallel with its faces, said layer projecting through all 60 the edges of said block and being bent sharply backwardly and extending at least to about the back face to afford areas for enmeshing bonding material immediately next to the edge areas in back of said layer.

65 2. A cast building block of substantial thickness reinforced by a flexible, reticulated metal layer embedded therein substantially parallel with its faces, said layer projecting through all 70 of the edges of said block and being bent sharply backwardly and thence inwardly over the back

face to afford areas for enmeshing bonding material immediately next to the edge areas in back of said layer and immediately next to the back face.

3. A cast building block of substantial thickness 5 reinforced by a flexible, reticulated metal layer embedded therein substantially midway of and parallel with its faces and being substantially coextensive with said faces, said layer projecting through all of the edges of said block 10 and being bent sharply backwardly and thence inwardly over the back face to afford areas for enmeshing bonding material immediately next to the edge areas in back of said layer and immediately next to the back face. 15

4. A cast building block of substantial thickness recessed inwardly at all of its edges in back of said front face to define a marginal shoulder and inwardly recessed edges, said block being reinforced by a flexible, reticulated metal layer 20 embedded therein substantially parallel with its faces and said layer projecting through all of said edges immediately in back of said shoulder and being bent sharply backwardly and extending at least to about the back face to afford 25 areas for enmeshing bonding material immediately next to the inwardly recessed edges.

5. A cast building block of substantial thickness recessed inwardly at all of its edges in back of said front face to define a marginal shoulder 30 and inwardly recessed edges, said block being reinforced by a flexible, reticulated metal layer embedded therein substantially parallel with its faces and said layer projecting through all of said edges immediately in back of said shoulder 35 and being bent sharply backwardly and thence inwardly over the back face to afford areas for enmeshing bonding material immediately next to the inwardly recessed edges and next to the back face. 40

6. A cast building block of substantial thickness recessed inwardly at all of its edges approximately midway of its thickness to define a marginal shoulder and inwardly recessed edges, said block being reinforced by a flexible, reticulated metal layer 45 embedded therein substantially parallel and coextensive with its faces and said layer projecting through all of said edges immediately in back of said shoulder and being bent sharply backwardly and thence inwardly over the back face to afford areas for enmeshing bonding material immediately next to the inwardly recessed edges and next to the back face. 50

7. A building structure comprising a backing, 55 bonding material on said backing, and cast facing blocks of substantial thickness laid in said bonding material, each said block being of substantial thickness and being reinforced by a flexible, reticulated metal layer embedded therein 60 substantially parallel with its faces, said layer projecting through all of the edges of said block and being bent sharply backwardly and thence inwardly over the back face and thereby affording areas enmeshing said bonding material immediately next to the edge areas in back of said layer and immediately next to the back face. 65
